ATTORNEY.

UNITED STATES PATENT OFFICE

FREDERICK M. VENZIE, OF PHILADELPHIA, PENNSYLVANIA

BUILDING STRUCTURE

Application filed April 14, 1931. Serial No. 529,915.

This invention, generally stated, relates to a building structure and has more especial relation to a floor construction.

One object of the present invention is to provide a floor construction in which pre-cast slabs of cementitious material may be manufactured at a central plant and shipped to point of erection, whereby unskilled labor may assemble the slabs expeditiously to thus lessen the erection costs of a building structure.

Another object of the present invention is to provide a novel form of floor slab in which it is not necessary in erection or placing of floor slabs to have the floor members accurately spaced.

A further object of the present invention is to provide a floor construction in which elongated floor slabs are reinforced both laterally and longitudinally considered throughout the length and breadth of a building structure.

A still further object of the present invention is to provide a floor construction made up of pre-cast elongated slabs which may be so arranged as to accept novel forms of metal clips for tying or coupling together adjacent slabs.

A still further object of the present invention is to provide a novel form of metal clip stamped from a single blank and having lugs or fingers extended therefrom to engage recessed portions of floor slabs including their reinforcements to interlock the slabs.

A still further object of the present invention resides in the provision of a novel form of elongated precast slabs each having embedded therein longitudinally thereof a channel the ends of adjacent channels being coupled together by means of a novel form of clip.

A still further object of the present invention is to provide a floor construction of the character stated in which the slabs are coupled together laterally by means of wire members which pass through said channels and over other channels arranged between adjacent slabs.

A still further object of the present invention resides in the provision of a structure of

the character stated in which flat cross-strips having apertured ends pass through said slabs, including the said central channel, and which apertured ends of adjacent slabs are coupled together by means of novel clips.

Other and further objects of the present invention reside in the provision of general details of construction and in the arrangement, combination, and connection of parts for attaining the results sought by the foregoing objects.

The invention consists of the novel construction hereinafter described and finally claimed.

The nature, characteristic features, and scope of the invention will be more fully understood from the following description taken in connection with the accompanying drawings forming part hereof, and in which:

Fig. 1 is a view in plan illustrating my novel form of flooring; 70

Fig. 2 is a view in section taken upon the line 2—2 of Fig. 1;

Fig. 3 is a view in section taken upon the line 3—3 of Fig. 1; 75

Fig. 4 is a view in section taken upon the line 4—4, Fig. 1;

Fig. 5 is a view in perspective of the novel form of clip shown in the foregoing figures;

Fig. 6 is a fragmentary view in plan, illustrating a modified form of coupling together slabs; 80

Fig. 7 is a view in longitudinal section of Fig. 6;

Fig. 8 is a fragmentary view, principally in section, illustrating a slightly modified form of tying together ceiling slabs; 85

Fig. 9 is a view in perspective of the clip in the modified form shown in Figs. 6 and 7; and 90

Fig. 10 is a fragmentary view, principally in section, illustrating a still further modified form of securing together the slabs from the sides thereof. 95

For the purpose of illustrating my invention, I have shown in the accompanying drawings forms thereof which are at present preferred by me, since the same have been found in practice to give satisfactory and re- 100

liable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 10 designates spaced floor members, as I-beams, which according to the present invention need not be accurately spaced. The reference numeral 11 designates pre-cast floor slabs of cementitious material of rectangular configuration and in practice are oblong, as illustrated.

In molding or casting the floor slabs 11, I embed therein a reinforcement longitudinally thereof comprising a so-called plasterer's channel 12 which extends from end to end of a slab. Each slab 11 is provided with a flanged portion 13 and in practice the bottoms of the channels 12 are in alignment with the tops of the flanges 13, as best seen in Figs. 3 and 4. The flanged portions 13 of the slabs 15 have arranged centrally with respect thereto a body portion the side walls of which are bevelled, as at 14. The bevelled sides 14 are vertically notched as at 15, which notches extend from the tops of the flanges to the 20 tops of said bevelled bodies. Arranged cross-wise of each slab 11 are a plurality of flat strips 16 the ends of which are slotted as at 17 and project into the slotted portions 15 of the slabs. In the connection it is to be noted that the cross-members or pieces 16 pass through slots in the central reinforcing channel 12, as best seen in Fig. 2. Each end of each slab is also vertically slotted as at 18, into which project the ends of the channels 12. Each end of each channel 12 is slotted as at 19, best seen in Fig. 2. These slotted ends of the channels rest upon the top of the flange 13 where said channels project into the slots 18. At these projecting points of the channels 12 I couple adjacent projecting ends together by means of a metal clip, as clearly illustrated in Fig. 5. Each clip is stamped from a single piece of metal and comprises a body portion 20 extended from 25 which at right angles thereto are spaced fingers 21. Each finger is bevelled as at 22 so that when the fingers 21 are introduced through the slots 19 of the channels 12, the bevelled portions in effect have a cam-like or gripping action, thus serving to securely couple the channels together. I make use of the same type of clip for connecting together the opposed slotted ends of the cross-members 16, as clearly illustrated in Fig. 1. In the connection it is to be noted that the slotted vertical portions 15 in the bevelled side walls of the slabs serve to provide convenient places in which the clips may be accommodated. Between adjacent slabs longitudinally with respect thereto I

position other plasterer's channels 23 which rest upon the tops of the flanges 13, as clearly shown in Fig. 3. These channels 23 extend from end to end of a building being erected. Laterally between adjacent ends of the slabs 11 I position members of wire having hooked ends 24 for engaging over the channels 23 upon opposite sides of each slab 11. These wire members are bent centrally thereof as at 25 so as to engage beneath the channels 23, as clearly shown in Fig. 3. This arrangement of parts serves to securely couple together laterally considered adjacent slabs 11.

From the above description it is apparent that efficiently reinforced square floor slabs may be tied or coupled together both longitudinally and laterally of a building structure to interlock the slabs in such manner that even though the floor beams are not equally spaced to permit adjacent edges of companion floor slabs to rest upon the floor beams, the efficient interlock of slabs overcomes this defect.

After the slabs 11 are properly positioned upon the floor beams 10 the space between adjacent slabs is filled in with cementitious material flush with the slab tops. In the connection it is to be noted that the slab sides are provided with longitudinal grooves so that when the cementitious material is introduced a key is formed between adjacent slabs.

Referring now more particularly to the modified form shown in Figs. 6 and 7, the slabs 11 have embedded therein longitudinally thereof reinforcing members 25. These reinforcing members at their ends are slotted as at 26. The slotted ends project beyond the ends of the slabs and overlap one another, as clearly shown in Fig. 6, so that the slots 26 of adjacent reinforcing members register one with another to accommodate clips 27, as best seen in Fig. 9. The clip, which is of metal and stamped from one piece, has a tapered end which when introduced through the registering slots of the reinforcing members 25 serves to couple the slabs together.

Referring now to the modified form shown in Fig. 10, the same clip 27 is employed in this construction as is employed in Figs. 6 and 7. For this purpose the slabs 11 have extended laterally therethrough reinforcing members 28 having slotted ends which project laterally beyond the sides of the slabs, with the slots registering one with another to accommodate the clips 27. When this construction is employed, no plasterer's channels are utilized for extending between adjacent sides of the slabs 11.

Referring now to Fig. 8, the same clip as shown in Fig. 5 is employed for coupling together laterally considered the slabs 11. However, in this construction of parts the reinforcing members 29, which are embedded

within and extend laterally of the slabs, have their slotted ends overlap and rest upon the upper face of plasterer's channels 23 with the intermediate portion of said reinforcing members passing through apertures within plasterer's channels 12 embedded within the slabs 11.

If desired, as plainly shown in Fig. 1, the slabs 11 at certain portions throughout their extent may be provided with lateral extensions 30 against which the plasterer's channels 23 abut, and use may be made of nails 31 for securing the plasterer's channels to said extensions 30 in order to provide rigidity of parts.

Referring now to Fig. 2, more especially, it is sometimes desired to anchor with respect to the floor beams 10 the plasterer's channels 12, and for this purpose I make use of metal clips 32 having notched bottoms for engaging beneath the upper flange of a floor beam 10 and having their upper ends hooked over the plasterer's channels 12. This arrangement of parts serves to prevent canting of the floor beams 10 in case of fire.

What is claimed is:

1. In a floor structure of the character stated, floor members, elongated pre-cast slabs of cementitious material arranged upon said floor members side to side in abutting relation, the sides of said slabs being bevelled and having vertical grooves therein, cross-strips of metal having slotted ends embedded in said slabs, said slotted ends being projected into said grooves, metal clips engaging adjacent cross-strips for coupling said slabs together, each clip comprising a flat plate having extended therefrom at right angles pendant fingers for engaging the grooves of said slabs, a longitudinal channel having slotted ends embedded in said slabs, and clips engaging the slotted ends of said channels for coupling together longitudinally said slabs.

2. In a floor structure of the character stated, floor members, elongated pre-cast slabs of cementitious material arranged upon said floor members side to side in abutting relation, the sides of said slabs being bevelled and having vertical grooves therein, cross-strips of metal having slotted ends embedded in said slabs, said slotted ends being projected into said grooves, metal clips engaging adjacent cross-strips for coupling said slabs together, each clip comprising a flat plate having extended therefrom at right angles pendant fingers for engaging the grooves of said slabs, a longitudinal channel having slotted ends embedded in said slabs, clips engaging the slotted ends of said channels for coupling together longitudinally said slabs, unembedded channels arranged between adjacent slabs longitudinally thereof, and cross-members arranged between adjacent ends of said slabs for engaging said unembedded channels, said cross-members passing beneath the embedded channels and over the unembedded channels.

ends of said slabs for engaging said unembedded channels.

3. In a floor structure of the character stated, floor members, elongated pre-cast slabs of cementitious material arranged upon said floor members side to side in abutting relation, the sides of said slabs being bevelled and having vertical grooves therein, cross-strips of metal having slotted ends embedded in said slabs, said slotted ends being projected into said grooves, metal clips engaging adjacent cross-strips for coupling said slabs together, each clip comprising a flat plate having extended therefrom at right angles pendant fingers for engaging the grooves of said slabs, a longitudinal channel having slotted ends embedded in said slabs, clips engaging the slotted ends of said channels for coupling together longitudinally said slabs, unembedded channels arranged between adjacent slabs longitudinally thereof, and cross-members arranged between adjacent ends of said slabs for engaging said unembedded channels, said cross-members passing beneath the embedded channels and over the unembedded channels.

4. In a floor structure of the character stated, floor members, elongated pre-cast slabs of cementitious material arranged upon said floor members side to side in abutting relation, the sides of said slabs being bevelled and having vertical grooves therein, cross-strips of metal having slotted ends embedded in said slabs, said slotted ends being projected into said grooves, a longitudinally arranged channel embedded in each slab, said cross-strips passing through said embedded channel, un-embedded channels arranged between adjacent slabs the free ends of said cross-strips resting upon the tops of said un-embedded channels, and metal clips engaging adjacent cross-strips for coupling said slabs together, each clip comprising a flat plate having extended therefrom at right angles pendant fingers for engaging the grooves of said slabs.
